UNITED STATES PATENT OFFICE

JERROLD LOEHL, OF CHICAGO, ILLINOIS, ASSIGNOR TO JOHN R. THOMPSON CO., OF CHICAGO, ILLINOIS, A CORPORATION OF WEST VIRGINIA

TABLE

Application filed February 28, 1930. Serial No. 432,003.

This invention relates to a table or a device providing a supporting surface and in its present form it is embodied in a dining table. It has for one object to provide a table in which a table top is mounted on a single supporting assembly and in which the top is so formed as to give the impression of being more than one table. Thus in one form of the invention the table top is so formed as to appear to be in fact not a single table top but the tops of two tables which have been pushed together.

It has been found in restaurants that it is difficult to persuade customers to sit at a table which is already occupied. Therefore, much space is wasted where single customers occupy a table which has a capacity of more than one person.

An object of the invention is, therefore, to from a table top in such manner as to give the impression of more than one table. Then if a party large enough to fill the entire table is seated, they are seated as though at a single large table. If, however, one person were to be seated first at such a table, another person could be later seated at the same table and because of the shape of the table top the effect is as though the customers were seated not at a single table but at two or more tables, made separately but placed close to or against each other.

Other objects will appear from time to time in the specification and claims.

My invention is illustrated more or less diagrammatically in the accompanying drawings, wherein:

Fig. 1 is a side elevation of a table;

Fig. 2 is a plan view of the same;

Fig. 3 is an end view;

Fig. 4 is a plan view of a modified form of table top;

Fig. 5 is a plan view of a further modification made on a smaller scale;

Fig. 6 is a modified form generally similar to Fig. 2, with some modifications;

Fig. 7 is a further modification;

Fig. 8 is a longitudinal cross section taken on line 8—8 of Figure 7;

Fig. 9 is a further modified form.

Like parts are designated by like characters throughout the specification and drawings.

A A indicate table legs. A¹ A¹ are stiffening and supporting frame members. B is a table top. In the form shown in Fig. 2 the top is generally rectangular in shape and is provided on two of its sides with indentations B¹ B¹. The table is further provided with a border B² which extends preferably entirely about the table and which is joined by a central portion B³ which may be of greater width than the border.

C C are portions of the table top which in some manner are made to appear distinct from the border. This might be done by making the border and the portions C C of different colors or by other treatment of the table top, for example, the borders might be smooth and the portions C might be rough.

The entire table top might be patterned with one pattern for the border and another for the parts C. For the purposes of the invention it is immaterial how the surface is treated so long as the borders B² and the portion B³ are different in appearance from the portions C. For some purposes, however, the entire table top might have the same appearance but the indentations B¹ would serve to divide the top in effect into two table tops. Thus the top is formed or treated or colored so as to give the impression that it is two table tops.

In Fig. 4 a modification appears in which a border D is provided about the entire table and a cross member D¹ extends transversely across the table and it may or may not be wider than the border D. Two other portions D² D² extend longitudinally of the table and are preferably joined to the border D and the portion D¹.

Portions E E, preferably four, are provided on the table top and they are separated from each other by the portions D¹ and D². Thus this table top gives the effect of being four small tables pushed together and it is provided with four indentations F F, two on its sides and two on its ends.

In Fig. 5 the modified form appears which is generally the same as that shown in Fig. 2 except that it gives the impression of three

tables. There are three portions G G, a border G¹ and two transversely arranged portions G² G². The table is provided along each of the its longer sides with two indentations H H.

In Fig. 6 there is illustrated a modified form somewhat similar to Fig. 2, but the surface treatment is different. I is the table top and it is provided with two indentations I¹ I¹ on its longer sides. No particular treatment is given to the top of the table, the indentations I¹ I¹ serving to give the impression of two tables. The surface may be the same throughout.

In Fig. 7 a table top J is shown which is provided in its top with a transversely extending depression J¹. There are no indentations on the sides or the ends and there is no particular surface treatment beyond the formation of the depressed band J¹. The form shown in Fig. 7 might have the indentations such as those I¹ I¹ of Fig. 6 added to it and the forms shown in Figs. 6 and 7 might further have the particular surface treatment of borders and central spaces such as shown in Figs. 2, 4 and 5 added. For some purposes, however, they may remain as shown in the drawings and the impression of two tables is adequately conveyed by the use either of the indentations alone or the depressed band alone.

In the form shown in Fig. 9, two table portions K K are provided. They are in effect rounded tables and are joined by a narrowed strip or band K¹.

It will be realized that while I have shown and described a practical working embodiment of my invention, nevertheless many changes might be made in the size, shape, number and disposition of parts without departing from the spirit of my invention. In particularly any combination of the various surface treatments shown might be used. While the invention is shown and described as being a table top and particularly a dining table top, it is not limited to such a use and the upper portions of other articles of furniture may be so formed and it is within the contemplation of my invention to make the upper portions of many different articles of furniture in this manner, where for any reason it is desirable to do so. I wish, therefore, that my description and drawings be taken as in a broad sense diagrammatic and not as limiting me to the specific forms shown.

I claim:

1. As a new article of manufacture, a table top having its upper surface formed into a plurality of generally plane areas, there being a portion separating such areas, said portion being on a plane different from that of the said areas.
2. As a new article of manufacture, a table top having its upper surface formed into a plurality of areas differing in appearance

from each other, one of said areas being disposed in a different plane from said other areas and defining two separated, relatively extended zones.

3. As a new article of manufacture, a table top having its upper surface formed into a plurality of generally plane areas, one of said areas being disposed intermediate two other areas, the latter two areas being similar in appearance, and both of them differing in appearance from said intermediate area, said intermediate area being disposed on a different plane from that of the adjacent areas, whereby to define two separated areas of similar appearance.

Signed at Chicago, county of Cook, and State of Illinois, this 21st day of February, 1930.

JERROLD LOEBL.
